UNITED STATES PATENT OFFICE.

JOHN H. VATERLAUS, OF FORT LEVETT, MAINE.

WINDOW-CLEANER.

1,248,759.

Specification of Letters Patent.

Patented Dec. 4, 1917.

Application filed April 13, 1916. Serial No. 90,879.

To all whom it may concern:

Be it known that I, JOHN H. VATERLAUS, a citizen of the United States, and a resident of Fort Levett, in the county of Cumberland, and State of Maine, have invented a new and useful Improvement in Window-Cleaners, of which the following is a specification.

My present invention relates to window cleaners and more particularly to that class embodying one or more squeegees, movable with respect to, but carried by the window pane, and adapted to remove snow, rain, or moisture from the pane of glass.

The principal objects of my invention are to provide a window cleaner of the character described which is simple in construction and inexpensive to manufacture, each cleaner embodying a plurality of parts which may be formed on the same die stamping machine, or from the same mold, when desired; a window cleaner of the character described which may be easily assembled and the squeegee bar or bars removed without dismembering the entire device, for the replacing of worn felt or rubber strips; and, a window cleaner which may be applied to panes of glass of different thicknesses.

Another object of my invention is to provide an improved squeegee bar for window cleaners which is firm throughout its length, and embodies means whereby the wiping element may be quickly placed or removed.

Other objects of the invention will appear in the following detailed description, taken in connection with the accompanying drawing, forming a part of this specification, and in which drawing:—

Figure 1 is a perspective view of the front portion of an automobile showing the application of my invention to the wind shield thereof.

Fig. 2 is a horizontal longitudinal sectional view through a portion of the pane of glass, showing the application of a window cleaner, constructed according to my invention, applied thereto.

Fig. 3 is a fragmentary front elevation of the cleaner.

Fig. 4 is a sectional view on the line 4—4 of Fig. 2.

Fig. 5 is a perspective view of a disk or

carrier, constructed according to my invention.

Fig. 6 is a fragmentary perspective view of the squeegee.

In the drawings, where similar characters refer to similar parts throughout the several views, A designates a pane of glass; B a hub passing therethrough; C disks or carriers revolvable with but movable longitudinally of said hub; D squeegees; E spring washers for pressing the squeegees against the glass A; F a nut having screw-threaded engagement with hub B for compressing spring washers E; and, G a knob serving as a lock for nut F.

While I have herein shown my invention as applied to a pane of glass, forming a part of a wind shield, it is to be understood that the invention is applicable to the windows of various types of vehicles, such as street cars, motor boats, etc., or can be applied to the windows of buildings, especially where it is desired to have a clear vision through the window as in switch houses, signal towers and the like. The pane of glass A is provided with a perforation 7, formed therein as by boring, or by means of a core when the glass is molded.

The main body portion 8 of hub B passes through perforation 7, which hub may also include a head 9, at one end, and a screw-threaded portion 10, opposite therefrom.

In the example shown, two squeegees D are used, one at each side of the pane of glass A, and therefore, two carriers or disks C are shown, one at or adjacent each face of glass, a compressible washer 11 being preferably interposed between the surface of the glass and the carrier, that is, one washer 11 at each face of the glass, the washers encircling the body portion 8 of hub B. Each disk or carrier, as clearly shown in Fig. 5, is provided with an opening 12 to receive the main body portion 8 of the hub; a keyway 13 open to said opening 12; and for the purpose of supporting the squeegee D, is provided with a radial recess 14, in one face, a plurality of screw-threaded bores 15 being disposed open to the bottom 16 of recess 14. In order that the disk or carrier C may be rotatable with but movable longitudinally of hub B, the pins 17 are provided, having screw-threaded engagement with the main

body portion 8, and entering the said keyways 13.

Referring now to the squeegee D, it preferably comprises a bar 18, substantially C-shaped in cross section; a flexible strip 19, such as felt or rubber, fitting into the hollow of the bar 18, and extending laterally beyond the side walls thereof, as at 20; a filler 21 for holding the strip 19 in intimate contact with the interior of the bar; and, means 22, such as screws passing through the filler 21, strip 19, and having screw-threaded engagement with the bar 19, at its crown portion. By extending the strip 19 beyond the side walls of the bar 18, as indicated at 20, a considerable surface of the flexible strip is in contact with the pane of glass A, so that, as the squeegee is moved over the surface of the glass, all snow, moisture or rain, will be wiped therefrom.

The squeegee is firmly supported from the disk or carrier C, by having one end portion cut away, as at 23, longitudinally at its edges, the reduced portion 24 fitting into the recess 14, with its edges resting upon the bottom of said recess, and engaging the side walls 25 thereof. This reduced portion is also provided with a plurality of perforations 26, axially alined with the screw-threaded bores 15, screws 27 having their shanks passing through the perforations 26 and in screw-threaded engagement with the disk or carrier C at the bores 15, the heads of said screws engaging the curved outer face, or crown of the bar 18, as clearly shown in Fig. 2. Thus, as the screws 27 are tightened, the tendency is to bring pressure upon the reduced portion 24, forcing its side walls into tight engagement with the side walls of recess 14, thus causing a tight screw-threaded engagement between the screws 27 and the threads of bores 15. The screws 27 are not apt to become loosened due to vibration, because of this spring action of the bar 18, and it is to be observed that said bar will remain rigid throughout its length owing to the curvature transversely.

Referring now to the spring washers E, they are shown as somewhat cup shaped in the present example, protecting the screws 27. They are provided with a plurality of radial slots 28 open at the peripheral edge, and in order that the squeegees D may be removed from operative relation with the disks or carriers C, such as for the replacing of worn flexible strips 19, said spring washers may also be provided with enlarged openings 29, axially alined with the screws 27, as clearly shown in Fig. 3.

One of the spring washers E rests against the face of one of the disks or carriers C, and also abuts against the head 9 of hub B. The other spring washer rests against a face 65 of the other disk or carrier C, and against

which spring washer, the nut F is turned tightly. Thus the springs have a tendency to force the disks or carriers C toward each other, firmly pressing the flexible strips 19 of squeegees D against the two faces of the pane of glass A. The knob G may be turned upon the screw-threaded portion 10 of hub B, into engagement with the nut F, and if desired, a set screw 30 may be provided, extending through the neck 31 of knob G, and in engagement with said screw-threaded extension 10. Thus the knob not only serves as a means to facilitate rotation or oscillation of the squeegees about the axis of hub B, but also serves as a lock for nut F, which is adjusted to bring the desired pressure upon the flexible strip of the squeegees.

In assembling the device, the one spring washer E is first placed upon the hub, to engage the head 9 thereof, and the pin 17 nearest said head is then positioned so as to extend into the keyway 13 of the one disk or carrier C which is also placed about the hub. One washer 11 is then placed next adjacent to the disk C and a portion of the main body of hub B is then passed through the perforation 7 of the pane of glass A. This is followed by placing the other washer 11 in place, and turning the other pin 17 into the main body portion 8 of the hub. Upon placing the other disk or carrier C and spring washers into operative relation to the hub, the nut F can be turned tight, as hereinbefore described, and knob G placed upon the screw-threaded portion 10. It is desirable that the thickness of flexible strip 19 be slightly greater than that of the washers 11, in order that the spring E may serve effectively in bringing the said strip into intimate contact with the pane of glass A. The squeegees may be easily removed without dismembering the entire cleaners by merely passing the point of a screw driver through the enlarged openings 29 of the springs, into operative relation to screws 27, and drawing the squeegee bars 18 radially from the disk or carrier C.

Changes in detail may be made without departing from the spirit or scope of my invention; but,

I claim:

1. A window cleaner comprising in combination, a hub adapted to pass through a perforation in a pane of glass and provided with a head at one end and a screw-threaded portion opposite thereto; a compressible washer about each end of said hub adapted to engage the opposite sides of said pane of glass; a disk next adjacent to each of said washers, each disk being rotatable with but slidable longitudinally of said hub; a squeegee carried by each disk adapted to bear against said glass; a spring washer about said hub and bearing against one of said disks, and abutting against the head of said

hub; a second spring washer about said hub and bearing against the other disk; and, a nut in engagement with the said screw-threaded portion of said hub and abutting 5 against said last-mentioned spring washer.

2. In a window cleaner, the combination 10 of a hub, a disk rotatable therewith, provided with a radial recess in its one face, with screw-threaded bores open to the bottom of said recess, a spring washer about said hub, bearing against the said face of said disk and provided with enlarged openings alined with the axes of the said bores of said disks, a squeegee bar provided with 15 a portion fitting into the said recess in said disk and provided with perforations axially

alined with the said bores thereof, and screws passing through said squeegee bar and engaging in the said bores of said disks.

3. In a window cleaner, the combination 20 of a hub including a main body portion adapted to pass through a perforation in a pane of glass, two removable pins carried by said hub, adapted to be positioned at opposite sides of the said pane of glass, two 25 carriers adapted to be located one at each face of said pane of glass and about said hub and each provided with a keyway to accommodate the adjacent pin, squeegees carried by said carriers, and means for forcing 30 said carriers toward each other.

JOHN H. VATERLAUS.
